(57) **CLAIM**

The ornamental design for a blank for forming a display as shown and described.

DESCRIPTION

FIG. 1 is a first rear perspective view showing a blank for forming a display in an assembled configuration.

FIG. 2 is a second rear perspective view showing the blank for forming a display of FIG. 1 in the assembled configuration.

FIG. 3 is a rear view of the blank for forming a display of FIG. 1 in an unassembled configuration.

FIG. 4 is a first front perspective view of the blank for forming a display of FIG. 1 in the assembled configuration.

FIG. 5 is a second front perspective view of the blank for forming a display of FIG. 1 in a partially assembled configuration.

FIG. 6 is a third front perspective view of the blank for forming a display of FIG. 1 in the assembled configuration.

FIG. 7 is a top view of the blank for forming a display of FIG. 1 in the unassembled configuration; and,

FIG. 8 is a perspective view of the blank for forming a display of FIG. 1 in the unassembled configuration.

(Continued)

The broken lines in the drawings depict fold lines and form part of the claimed design.

1 Claim, 8 Drawing Sheets
